(57) **CLAIM**

The ornamental design of a transaction card presentation box, as shown and described.

DESCRIPTION

FIG. 1 is a front, top, left perspective view of a transaction card presentation box in a closed position, showing our new design;

FIG. 2 is a top view thereof;

FIG. 3 is a bottom view thereof;

FIG. 4 is a left side view thereof;

FIG. 5 is a right side view thereof;

FIG. 6 is a front side view thereof; and

FIG. 7 is a back side view thereof.

FIG. 8 is a front, top, left perspective view of the transaction card presentation box in a partially open position, and

FIG. 9 is a top, right, back perspective view thereof.

FIG. 10 is a front, top, left exploded perspective view of the transaction card presentation box in a partially open position;

FIG. 11 is a top view of FIG. 8;

FIG. 12 is a top view of FIG. 10;

FIG. 13 is a bottom view of FIGS. 8 and 10;

FIG. 14 is a left side view of FIGS. 8 and 10;

FIG. 15 is a right side view of FIGS. 8 and 10;

FIG. 16 is a front side view of FIGS. 8 and 10; and

FIG. 17 is a back side view of FIGS. 8 and 10.

FIG. 18 is a front, top, left perspective view of the transaction card presentation box in fully open position;

FIG. 19 is a front, top, left exploded perspective view thereof;

FIG. 20 is a top view of FIG. 18;

FIG. 21 is a top view without the insert;

FIG. 22 is a bottom view of FIGS. 18 and 19;

FIG. 23 is a left side view of FIGS. 18 and 19;

FIG. 24 is a right side view of FIGS. 18 and 19;

FIG. 25 is a front side view of FIGS. 18 and 19; and,

FIG. 26 is a back side view of the third embodiment shown in FIGS. 18 and 19.

(Continued)

The broken lines are included for the purpose of illustrating portions of the transaction card presentation box and form no part of the claimed design.

1 Claim, 26 Drawing Sheets
